UNITED STATES PATENT OFFICE.

LOVREN E. HOGUE, OF GREENVILLE, PENNSYLVANIA.

INJECTOR.

No. 834,133.

Specification of Letters Patent.

Patented Oct. 23, 1906.

Application filed September 23, 1905. Serial No. 278,821.

To all whom it may concern:

Be it known that I, LOVREN E. HOGUE, a citizen of the United States, residing at Greenville, in the county of Mercer and State of Pennsylvania, have invented a new and useful Injector, of which the following is a specification.

This invention relates to boiler-feeding injectors, and has for its principal object to simplify the construction of the injector and to so arrange and construct the parts as to provide for the ready passage of the overflow at a point close to the water-inlet.

A further object of the invention is to provide an injector in which a free passage is afforded the steam in escaping at the beginning of the operation, and, further, to provide independent valved outlets for both the cold and the hot water overflow.

A still further object of the invention is to provide a novel form of forcing-tube so arranged as to permit the passage of hot water to the overflow at the beginning of the operation while preventing the passage of the water to the overflow when at boiler-pressure.

A still further object of the invention is to provide an injector of very simple and economical construction having connections similar to those employed on standard injectors, so that it may be readily substituted therefor without any change in the piping or other connections.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a vertical section of an injector constructed in accordance with the invention. Figs. 2 and 3 are transverse sectional views of the same on the lines 2 2 and 3 3, respectively, of Fig. 1.

Similar numerals of reference are employed to indicate corresponding parts throughout the several figures of the drawings.

The main casing 10 of the injector is provided with a steam connection 11 and a wa-

ter connection 12, these being arranged at diametrically opposite points, as commonly practiced in the Metropolitan and other standard injectors. Near the rear of the casing is a transversely-extending partition 13 to divide the steam and water inlets, and in said partition is an opening for the reception of the steam-tube 15, the latter having an enlarged shoulder 16, that fits against the steam side of the partition, while the end of the steam-tube projects across the water-inlet chamber.

At the end of the casing is a threaded opening for the reception of a stuffing-box member 18, through which passes the steam-valve stem 20, the latter being connected in the usual manner to an operating-lever 21. The opening in which the stuffing-box member 18 is screwed is of sufficient diameter to permit the insertion of the steam-tube 15, the latter being forced into place, or, if necessary, being provided with screw-threads to insure its remaining in proper position.

Near the rear end of a barrel 23 of the injector is a transverse partition 24, having a threaded opening for the reception of the threaded periphery of a lifting-tube 25, the wider end of the latter facing the steam-tube and an annular space being formed between the two through which the water may pass from the water-chamber. In order to prevent overheating of the water in the water-chamber, a portion of the partition 13 is cored out, as indicated at 26, so that the water cannot be heated by direct radiation from the steam.

In the pump-barrel is a second transverse partition 30, having a threaded opening for the reception of a threaded flange 31 on the forcing or combining tube 32, the opening in the partition 30 being of sufficient diameter to permit the ready passage of the lifting-tube 25.

The partition 30 divides the main barrel of the injector into two compartments 34 and 35, and at one side of the compartment 34 is an overflow-opening 36, while at the opposite side of the compartment 35 is an overflow-opening 37 for the passage of the hot water overflow.

The outer face of the barrel 23 is turned in order to receive the casing 38 of the overflow-chamber 39, and from said casing leads an outlet 40 to permit the escape of the water and steam. The overflow-casing may be held in place by bolts 41, and is so arranged

in connection with the overflow-outlets 36 and 37 that there is no danger of the setting up of a circulation of water between the outlets, which might otherwise occur if both 5 openings were arranged on the same side of the barrel. In the present instance, however, any water passing through either of the openings will flow instantly to the discharge-opening 40.

10 The openings 36 and 37 may be closed by pivoted valves 42, that are curved to follow the contour of the barrel, and will close gently by gravity, said valves being so arranged as to offer practically no resistance to the passage of the overflow-water, but close tightly 15 on the condensation of the steam within the barrel in order to prevent the entrance of air. These valves may be locked during cold weather by set-screws 44 when it is desired to allow a small quantity of steam to flow down through the inlet-pipe 12 to the tank to prevent the parts from freezing.

15 The tube 32, which is a combined forcing and delivery tube, projects partly within the chamber 34 and is provided with openings 45 to permit the passage of steam. At the outer end of the tube is a disk 46, which is held against the end of the barrel by the casing 47, which supports the check-valve 48. The 20 disk and tube 32 are formed integral, and at the outer face of the disk is a boss 49, having a square or hexagonal surface to be engaged by a wrench in inserting the tube.

25 The largest diameter of the tube is within the chamber 34, and from this the tube tapers on convergent lines toward the point 50 and from thence on convergent lines at a lesser angle toward the point 51 and thence on parallel lines toward the point 52 and 30 thence on divergent lines toward the end of the tube, this portion forming the delivery-tube.

35 Immediately beyond the point in intersection of the two angles 50 are arranged a number of openings 55 for the passage of water and steam, and beyond the point 51 are openings 56, while within the line 52—that is to say, in advance of the delivery portion of the tubes—are arranged openings 57, 40 all of these openings permitting the free passage of water and steam to form the hot-water overflow, the water escaping until the pressure is sufficient to overcome the boiler-pressure; but it will be noted that in each 45 case the openings are so arranged that they do not aid in the escape of the water while the stream is converging, this being especially true of the openings 57, which are arranged in advance of the beginning of the 50 delivery portion of the tube. If arranged beyond that point, the water passing, being at boiler-pressure, will tend to expand backward and pass through the openings.

The water-pipe 12 is provided with a but-

terfly-valve 59, by which the quantity of 65 water entering the injector is controlled.

In operation the valve-stem 20 is opened to allow steam to enter the steam-tube 15, and this steam in passing through the lifting-tube 25 will enter the chamber 34 and will 70 open valve 42, escaping through the overflow-opening. On the admission of a small quantity of water the steam is condensed, forming a vacuum which will draw in more water, and this water will first pass through the tube 75 25 in the chamber 24 and through the overflow-opening 36. As the steam continues to act it will force a stream of water into the tube 32, mingling therewith, and a portion of this hot water and steam will flow through 80 the openings in the tubes to the chamber 35 and thence pass through the opening 37 to the overflow. The rapid condensation of the steam, however, will create a partial vacuum within the overflow-chamber, and the barrel 85 and the valves 42 will be moved to closed position and held closed by atmospheric pressure in order to prevent the entrance of air.

90 The boiler check-valve is preferably placed at some little distance from the delivery-tube in order that the stream may be given sufficient impetus or momentum to quickly open said valve, it being found in practice that the injector is in full working condition 95 within two seconds of the initial opening of the steam-valve, so that but a trifling amount of water is wasted at the overflow.

95 In manufacturing the injector the main casing or barrel 23 is turned and finished on its outer face, and the overflow-casing 38 is likewise finished on its inner face and when forced onto the barrel forms a tight joint therewith. The outwardly-projecting portions of the overflow-casing arranged opposite the overflow-openings leading from the barrel are designed to receive the valves 42. These valves are usually made by casting an annulus of brass or similar material and turning or finishing the inner face thereof to correspond to the curvature of the barrel. The annulus is then divided into sections, each section forming a valve, and the valves are hinged to the overflow-casing in such manner that when the latter is placed in position they 110 will fit snugly against the outer face of the barrel. 115

Having thus described the invention, what is claimed is—

1. In an injector, a casing having independent hot and cold water overflow openings arranged on opposite sides, respectively, of the casing to prevent the setting up of circulation through the casing and openings, and separate self-closing valves for said openings. 120

2. In an injector, a casing, a forcing-tube mounted within the casing, a partition ex- 125

tending across the casing and carrying said forcing-tube, the partition dividing the casing into two compartments, there being independent overflow-openings leading from 5 opposite sides, respectively, of said compartments, and separate self-closing valves for said openings.

3. In an injector, a casing having an approximately central partition dividing the 10 casing into hot and cold water overflow compartments, a forcing-tube mounted in the partition and having perforations leading to both chambers, and valved overflow-openings leading from opposite sides, respectively, 15 of said chambers.

4. In an injector, a casing having steam and water inlets, a partition dividing the casing into two chambers, a forcing-tube carried by the partition and provided with perforations leading to both chambers, a lifting-tube arranged in advance of the forcing-tube and having its inner end opening into one of said compartments to permit the direct passage of steam and cold water, an overflow-chamber mounted on the casing and having an 25

outlet for the escape of steam, and a hot and cold water overflow, and valved openings arranged at opposite sides, respectively, of said chambers.

5. In an injector, a casing having steam 30 and water inlets, and a barrel, the upper face of which is finished, said barrel being provided with hot and cold water overflow openings arranged one at one side, and the other at the other side of the barrel, an overflow- 35 casing mounted on the periphery of the barrel and having recessed portions facing the openings, and valves formed of metallic segments, the upper ends of which are pivoted to the casing, the concaved faces of said segments resting against the periphery of the barrel and serving to close the overflow-openings.

In testimony that I claim the foregoing as my own I have hereto affixed my signature in 45 the presence of two witnesses.
